UNITED STATES PATENT OFFICE

139,997

DESIGN FOR A DETACHABLE COLLAR

Harry Inverne, New York, N. Y., assignor to Bar-berry Fashions, Inc., New York, N. Y.

Application November 7, 1944, Serial No. 116,203

Term of patent 14 years

(Cl. D13—8)

To all whom it may concern:

Be it known that I, Harry Inverne, a citizen of the United States of America, residing at New York, in the county of New York and State of New York, have invented a new, original, and ornamental Design for a Detachable Collar, of which the following is a specification, reference being had to the accompanying drawing, forming part thereof.

In the drawing:

I claim:

The ornamental design for a detachable collar, as shown.

HARRY INVERNE.
